W. Klink

UNITED STATES PATENT OFFICE.

WILHELM KLINK, OF HAMBURG, GERMANY, ASSIGNOR TO HERMANN HEGELER, OF OLDENBURG, GERMANY.

PIANO-VIOLIN.

No. 900,021.

Specification of Letters Patent.

Patented Sept. 29, 1908.

Application filed May 17, 1907. Serial No. 374,190.

To all whom it may concern:

Be it known that I, WILHELM KLINK, a subject of the German Emperor, and resident of No. 30 Grosse Reichenstrasse, Hamburg, 5 Germany, have invented certain new and useful Improvements in and Relating to Piano-Violins, of which the following is a specification.

The present invention relates to improvements in stringed instruments of one string. 10 In the former instruments of this kind the effect of the key-board, as well known, was transmitted onto the string pneumatically whereas in this invention the effect is derived mechanically by the aid of levers and 15 the like manipulated by keys from a key-board while the string is sounded by a rotating roller or running band.

The accompanying drawing gives a representation of the invention, in two forms of construction.

Figure 1 shows a form of construction in which the string is touched by a roller having a ring of horse-hair or the like on its periphery. Fig. 2 shows another form of construction with a band of horse-hair, silk or the like running over two rollers which rotate in an arm which keeps stretched the running band by any suitable device. Fig. 3 is a section 30 to show clearly the relation between the presser (c) and the string.

The invention consists in the instrument or violin (a) having only one string, being supported on a suitable stand and arranging, 35 over its finger-board (b), a plurality of finger-rod (c), influenced by springs and guided in guides which are adapted to touch the string when manipulated by the respective keys connected with the bars (f) which are 40 operatively connected with the levers (e) and (d) arranged over the said rods. Below the levers (e) a yoke (g) having a counter-weight (h) is pivoted. The yoke (g) bears a pin (y) which rests on the movable bearing arm of the 45 roller and presses down the latter, when a key on the key-board is moved, in such a manner that, during the depression of a key, the said yoke is lowered with the lowering of the respective finger-rod (c) in such a way 50 that the rollers (i') and (k) (Fig. 2) having a running band of horse-hair or the roller (i) (Fig. 1) alone having a ring of horse-hair, touches the string of the instrument whereby the latter is caused to sound.

The size of the rollers is chosen in such a way that the band runs free of the string which, only when the roller or rollers are depressed, is touched near the bridge, and the band, on the rollers, is rubbed with colophony by a device (v) arranged thereon in any suitable manner. (Fig. 1).

The manner of working the instrument is as follows: When the keys are manipulated from the key-board, the bars (f) work the levers (e); which are arranged upon the yoke (g), transmitting a corresponding movement on the fingering rods, (c) by the levers (d) whereby the roller or rollers, lowered in the movement, sounds the string according to the key which is moved. When the key is set free, the fingering rods (c) are lifted by springs (u). In this instrument the band is kept stretched by any suitable device. The device which works like a bow, on this instrument, can be set in motion by a treadle arrangement, and if this device is inserted or arranged in a piano, it can be driven by springs instead.

This invention can be arranged and employed to play like or in orchestrions, zithers, and the like, and also in electrically playing pianos of any construction and its mechanism can be coupled with that of the latter.

I claim:

In a stringed instrument the combination of a stand, a violin having one string arranged on this stand, a finger-board arranged on said stand, a plurality of fingering rods (c) arranged over the string and the finger-board, springs (u) normally raising the fingering rods, guides which guide the rods over the string, a plurality of pivoted levers (d) to operate the fingering rods respectively, a plurality of levers (e) to operate the levers (d) respectively, a plurality of bars (f) movably connected with the levers (e), a plurality of keys movably connected with the bars (f), a device having a driving roller (p), rollers operatively arranged in the said device, a band passing around the rollers and normally held slightly away from the string, a pivoted and counterweighted yoke, connections between the levers and the yoke and means for holding rosin on the band.

WILHELM KLINK.
